(57) **CLAIM**

The ornamental design for a foldable laptop stand, as shown and described.

DESCRIPTION

FIG. 1 is a front view of a foldable laptop stand, embodying my new design;

FIG. 2 is a front view thereof, but in an assembled position;

FIG. 3 is a front, right side perspective view thereof;

FIG. 4 is a front, top view thereof;

FIG. 5 is right side perspective view thereof, the left side perspective view being a mirror image;

FIG. 6 is a front, top view of the foldable laptop stand in a second assembled position; and,

FIG. 7 is a right side perspective view thereof; the left side perspective view being a mirror image.

The broken lines are included for showing features that form no part of the claim.
